PEACH CUTTER AND STONER.

No. 474,927.

Patented May 17, 1892.

UNITED STATES PATENT OFFICE.

JAMES HENRY SMITH, OF LITTLE ROCK, ARKANSAS.

PEACH CUTTER AND STONER.

SPECIFICATION forming part of Letters Patent No. 474,927, dated May 17, 1892.

Application filed August 13, 1891. Serial No. 402,504. (No model.)

To all whom it may concern:

Be it known that I, JAMES HENRY SMITH, a resident of Little Rock, in the county of Pulaski and State of Arkansas, have invented 5 certain new and useful Improvements in Peach Cutters and Stoners; and I do hereby declare the following to be a full, clear, and exact description of the invention, such as will enable others skilled in the art to which 10 it pertains to make and use the same.

The invention relates to machines for separating the meat or pulp of fruit—such as the peach—from its stone; and its object is to increase the capacity, efficiency, and economy 15 of such machines.

The invention consists in the construction hereinafter described, and particularly pointed out in the claims.

In the accompanying drawings, Figure 1 is 20 a partial vertical section of the machine, and Fig. 2 is a section on line 2 2 of Fig. 1. Fig. 3 is a sectional detail showing a modification. Fig. 4 is a perspective of the machine with a modified detail. Fig. 5 is a side elevation of 25 the detail. Fig. 6 is a perspective of a detachable stripping device, and Fig. 7 is a like view of a lever provided with curved stripping-blades.

Numeral 1 indicates a table, preferably of 30 oval or oblong form and supported upon legs 2. Upon this table is secured an iron frame composed of four posts 3, curved inwardly and united at their upper ends and formed into a sleeve 4. Preferably the sleeve, frame, 35 and table are cast in one piece, though this is not essential.

5 is an arm, which may also be cast with the sleeve and frame. In this arm at 6 is pivoted a lever 7, to which is pivotally attached the 40 plunger 8, which passes through a suitable opening in the sleeve or guide 4.

6' is a curved slot in lever 7, adapted to receive the pivot 6".

9 indicates a spring secured to the frame 45 and also to the plunger and arranged in such manner that it will be compressed by the descent of the plunger. The foot 10 of the plunger may be provided with a shallow depression adapted to receive the end of the 50 stone of a peach or of any similar fruit.

11 indicate strippers or scraping-levers provided with blades 16, adapted to force the

pulp from the stone when the machine is suitably operated. These strippers are by preference four in number, arranged in planes at 55 or nearly at right angles to each other, as shown in Fig. 2. They may be diagonally arranged, as indicated in Fig. 3. Each is a rigid bar of metal pivoted at 12 in a stud 13, and has an arm or extension 14 upheld by a spring 60 15. The several bars or strippers are so shaped and arranged that the springs normally hold their upper ends or blades 16 in proximity, as represented. The blades are slightly curved to correspond to the shape of 65 the fruit-stone, and are provided each with a slightly-rounded edge to enable it to slip over the rough surface of the stone. Fixed upon the rod or plunger is a sleeve 17, provided with brackets 17', in which are pivotally-supported levers 17", adapted to support the axis 70 of the revoluble blades 18. Springs 19 hold these levers so that the circular blades are normally in proximity to each other.

20 indicates a hole in the table located directly beneath the blades and punch.

21 is a spout adapted to receive and discharge the stones dropped from the blades.

In operation a peach, for example, has its stem end placed on and between the blades 16 in such position that the circular blades 18 are in a plane transverse to the width of the stone or transverse to a plane passing centrally through it and through the seam of the peach. The fruit being so placed, the plunger can be quickly driven down upon it while held between the thumb and finger of the operator with the effect to punch the stone out of the same, the pulp or meat being stripped or scraped off by the blades 16. Guides 16' 80 85 90 may be provided to prevent any part of pulp from falling through the hole 20. The stone falls into the spout and is conducted to a suitable receptacle, and the flesh of the fruit drops outside of the blades, and may be received in 95 a vessel beneath the table. The hand can be removed from the peach as soon as the punch presses upon the stone, the operation being immediately completed and altogether consuming but an instant of time. The blades 100 18 cut the flesh of the fruit in halves, and the blades 16 strip or scrape it clean from the stone. The punch may be made with a diameter of about three-eighths of an inch.

11 indicate strippers or scraping-levers provided with blades 16, adapted to force the

The machine is made of cast-iron and steel and is very durable. It is inexpensive and can be repaired by workmen of ordinary skill. It acts very efficiently, and it is adapted to fruits varying greatly in size, owing to the large movement of the blades 16, rendered possible by the particular form of the blade-levers and their combination with the coiled spring. The use of four blades having the angular arrangement shown and described provides, in connection with the spring, for an automatic adjustment in four different planes, and such that fruit of very large or very small sizes can be successfully operated upon without any rearrangement of the blades.

My invention is intended more especially for clingstone peaches, the flesh of which cannot be cut into halves and removed from the stone with an ordinary knife; but the machine will also cut and stone freestone fruit by the aid of the following-described attachments:

22 are detachable strippers suitable for freestone fruit. They are made of sheet metal in the form of a wedge having an oblique edge. They are removably fastened upon the blade-levers 17", as indicated, and in such relation to the blades 18 that their inclined edges can be forced into the cut made by the blades 18, with the effect to push or strip the pulp from the stone. For this operation the punch 10 is removed, and a fruit-support 23, which may be a wooden peg with a head, is inserted between the strippers 11, which are thereby rendered inoperative, except as a support for the peach. In this operation the entire flesh of the fruit is removed, and the stone and flesh fall upon the table together.

I am aware that spring blades or levers secured to a table have been used to stone peaches, and also that corn-shelling devices embracing bent levers pivoted at their angles and held against the cob by springs are old, and such devices are not broadly of my invention. It is a characteristic of my improvement that each blade-lever, which is of an approximately bell-crank form, has a sharp bend near its angle of such character that it provides a recess above the lever at the angle formed by its arms for the reception of a pivot, the same bend providing also that the horizontal arm shall be sufficiently above the table to which the lever is pivoted to permit a spring to be interposed between said arm and table. (See Figs. 4 and 7.) This spring is simply fastened to the arm and table without guiding-rods, brackets, or retaining-nuts, and is free to bend in a vertical plane; and, further, the lever is so pivoted as to provide for a slight movement in such plane, while the pivot-lugs are adapted to receive lateral strain without the necessity of any special device therefor. The above-described man-

ner of retaining the angle of the lever between lugs by a pivot held in a suitable bend 65 not only allows the lever to have a small lateral play, but obviates the weakening of the lever by a pivot-hole, and permits a lighter lever to be used.

Having thus described and ascertained the 70 nature of the said invention and in what manner the same is to be operated, it is declared that what is claimed is—

1. The combination of the table, the frame having a guiding-sleeve, the punch, the bent 75 levers 11, arranged in planes at about right angles to each other, said levers being pivotally supported between studs on the table, the pivot passing above the lever and within a bend therein and having each a horizontally-80 arranged arm 14, curved upwardly from the fulcrum of the lever, and a curved blade at the extremity of its opposite arm, and the springs, each having one end secured directly to the table and the other to the lever-arm 85 and adapted to permit a horizontal movement, adapted to lift said arms and hold the blades in proximity to each other, substantially as set forth.

2. In combination, the table provided with 90 studs 13, the levers 11, having each an approximately vertical arm provided with a stripping-blade and an arm 14, curved upwardly from the foot of the said vertical arm and having its main part horizontally disposed, and a spring having one end secured directly to the table and the other end to the lever-arm, being free to move horizontally and adapted to lift the arm 14, said curved portion between the arms being located between the studs and adapted to receive above itself within its curved part a securing-pin 95 passing through said stud, substantially as set forth.

3. In combination, the plunger, the lever 105 17", pivoted to said plunger and provided with blades, the wedge-shaped strippers, the bars 11, and the fruit-support, adapted to rest on said bars, substantially as set forth.

4. In combination with a fruit-stoning machine, the detachable strippers 22, having form of a wedge with an obliquely-disposed edge and levers 17, substantially as set forth.

5. In combination with a fruit-stoning machine, the detachable strippers 22, having the 115 form of a wedge with an obliquely-disposed edge and with the bars 11 and the headed peg 23, adapted to be supported by the bars and levers 17, substantially as set forth.

In testimony whereof I have signed this 120 specification in the presence of two subscribing witnesses.

JAMES HENRY SMITH.
